UNITED STATES PATENT OFFICE

ANDREW MYERSTUEN, OF SEATTLE, WASHINGTON

SHIP'S PILOT LADDER

Application filed May 8, 1928. Serial No. 276,174.

This invention relates to new and useful improvements in ships' pilot ladders, and to an improved step therefor as a new article of manufacture.

5 The object of this invention is an improved form of pilot ladder.

Another object of this invention is a portable ship's ladder consisting of but few parts, which may be readily assembled into the completed ladder.

Another object of this invention is a foldable, portable ship's ladder having but few, readily interchangeable parts, of durable material and durable in construction.

15 Another object of this invention is a new article of manufacture comprising a readily clamped step or tread for a portable ship's ladder.

In the drawings comprising two sheets, 20 numbered Figs. 1 to 6 inclusive,

Fig. 1 is a plan view of a step or tread embodying one form of the invention;

Fig. 2 is a sectional view of the step or tread taken along the line 2-2 of Fig. 1 looking 25 in the direction of the arrow;

Fig. 3 is a front view of a fragment of a ladder constructed in accordance with the embodiment of the invention in Figs. 1 and 2;

Fig. 4 is a plan view of a modification of the 30 invention; and

Fig. 5 is a partial rear view of the modified form illustrated by Fig. 4; and

Fig. 6 is a side view of the device of Fig. 5 viewed from the left.

35 Like characters of reference represent corresponding parts throughout the several figures.

The ship's pilot ladder herein set forth consists essentially of a pair of flexible cables 40 9 of any desired length. The cables 9 may be made of any preferred material either metallic or non-metallic, but in the form at present preferred these cables will consist of twisted wire strands composing flexible metallic cables.

Secured to the said cables at suitable intervals are a plurality of steps or treads 6 preferably of light metallic construction. These treads are of any preferred length and width 50 but an inside dimension measured between

the inner faces of the elements 7, of approximately fourteen and one-half inches, affords a satisfactory clearance.

The step 6 is roughened upon its upper side to constitute the tread surface and is hollowed or channelled upon its under side as is indicated by the line 12 in Fig. 2, to eliminate unnecessary weight without sacrificing strength and durability.

To secure the tread 6 to the cables 9 it is provided adjacent its outer ends with bracket members 7 positioned substantially at right angles to the plane of the tread 6.

The bracket members 7 are provided with a V-shaped recess adapted to receive the cable 9. Each bracket is also provided with holes adapted to receive the nut and bolt 8.

To secure a step to the cables 9 a pair of treads 6 are merely placed back to back with the cables 9 positioned within the V-shaped channels 10; the bolts 8 are then inserted through the holes in the brackets 7 and their associated nuts are then tightly screwed upon the bolts to clamp the brackets 7 carrying the treads 6-6 upon the cables.

With a plurality of steps secured to the cables 9 at suitable intervals (e. g., approximately twelve inches) apart the result will be a ladder of the desired length appearing in accordance with the construction shown in Fig. 3. When constructed in this manner employing double treads in accordance with the disclosures of Figs. 1 and 2, the ladder is in effect reversible and may be mounted from either side.

In the modification disclosed in Figs. 4 and 5 and 6 one of the treads 6 and its associated brackets 7 is omitted from each step and a clamping member 13 is substituted for the bracket member 7 thus omitted. This clamping member 13 is likewise provided with a V-shaped recess as indicated at 14, Fig. 4, so that when a pair of clamping members 13 are used in conjunction with the brackets 7-7 of a typical tread 6 the latter may be secured to the cables 9-9 by means of a plurality of nuts and bolts 8. A plurality of treads 6 when thus assembled on the cables 9-9 will constitute a portable ladder the length 100

whereof will depend upon the length of the cables employed.

Each of the clamping members 13 is recessed upon the outside as indicated at 11 in Fig. 5 to furnish a finger grip for the individual who is mounting the ladder.

Each bracket 13 is preferably provided with a spur-shaped projection 15 constituting means for spacing each clamping member 13 away from the ship's side. This construction has several advantages—among others, it affords sufficient clearance to permit the fingers to be inserted in the grip 11, it acts as a fulcrum for the step, to permit the latter to tilt slightly towards the ship's side under the weight of the climber, so that in his progress up the ship's side the climber's center of gravity is toward the ship rather than away from it.

20 The V-shaped channels may if preferred be roughened as indicated at 10 and 14 in Fig. 4, in order to increase the gripping action of the bracket and clamps and the cables 9.

25 It thus appears that the ship's ladder of the present invention consists of but few and simple parts, which are interchangeable, and which may be readily assembled without requiring the employment of skilled labor in 30 the operation. It also appears that a new part may be readily substituted for a defective part and that this substitution may be effected without interfering with other parts which are in good condition.

35 What is claimed is:

As a new article of manufacture a step for a ladder, said step being channelled upon its under side and having its upper surface roughened to constitute a tread, angular 40 bracket members integral with said step, each bracket member being provided with a groove adapted to receive one of the supporting side members of the ladder and with means coacting with the groove to lock the 45 side members against movement with respect to the bracket.

Signed at New York, in the county of New York and State of New York, this 4th day of May, A. D. 1928.
